UNITED STATES PATENT OFFICE.

CHARLES A. SPLAYFORD, OF VANCOUVER, BRITISH COLUMBIA, CANADA.

SNOW-PLOW.

1,243,355.

Specification of Letters Patent. Patented Oct. 16, 1917.

Application filed June 6, 1917. Serial No. 173,169.

To all whom it may concern:

Be it known that I, CHARLES A. SPLAYFORD, a citizen of the Dominion of Canada, residing at Vancouver, in the Province of 5 British Columbia, Canada, have invented certain new and useful Improvements in Snow-Plows, of which the following is a specification.

This invention relates to a snow plow which has been particularly designed for mountain use where difficulty is experienced in dealing with the great variation in the depth of the snow. The ordinary rotary snow plow, adapted to deal with deep drifts, has 10 a wheel of considerable diameter and although it reaches as close as practicable to the rail level it is ineffective in dealing with snow of a less depth than four feet as it merely churns it up without throwing it 15 clear of the track, and as a consequence these plows are frequently stalled in two or three feet of snow before they can reach the heavier drifts where their services are required and where they would be fully effective.

It is to enable a rotary plow to deal effectively with snow of any depth from a few inches over the rail, that the plow, which is the subject of this application, has been devised.

The essential features of it reside in the use with a bladed wheel, of an incline from adjacent the track level to a little below the axle of the bladed wheel by which the snow 35 is thrown laterally off the track, up which incline a conveyer travels drawn by the same engine which drives the rotary wheel.

The invention is particularly described in the following specification, reference being 40 made to the drawings by which it is accompanied, in which:

Figure 1 is a vertical section through the plow on a plane adjacent and parallel to the middle line.

Fig. 2 is a plan of the same.

Fig. 3 is a vertical cross section on the line 3—3 in Fig. 1.

Fig. 4 is a section on the line 4—4 in Fig. 1, and

Fig. 5 is a transverse section of the wheel.

Fig. 6 is an enlarged detail view of a portion of the invention.

In these drawings 2 represents the front end of a steel flat car on which the plow is mounted, of which car, 3 is the leading truck. The structure of the plow is built

onto this flat car and comprises side walls 4 of double steel plates spaced apart by channel irons except at the forward upper edge where the plates are riveted together. These 60 side walls have a profile, as shown in Fig. 1, and are secured to the sides of the car 2 outside the truck wheels. They extend backward for about half the length of the car and project in front of the leading end of the 65 car in a wedge shape form, as shown, and have a gap on each side just behind the trailing wheels of the car truck 3 where the rotary wheel 17 delivers to either side as required.

On the middle line between the two side walls and secured likewise to the front end of the flat car is a mid-partition 5, the upper side of which partition conforms generally to the corresponding profile of the side 70 walls 4 in advance of the rotary wheel gap. Across the front ends of the side walls 6 and mid-partition 5 is secured the horizontally disposed share 14 of the plow incline. The underside of this share is provided with 75 renewable slippers 15, which, when the plow is under load, as when cutting through a heavy drift, support the front end by bearing upon the track rails.

Secured between the sides walls 4 and the 80 mid-partition 5 are the two inclined chutes 6 sloping upward from the share 14 to the front edge of the gap about half the radius of the rotary wheel below its driving shaft, and over each chute travel the angle iron 90 cross bars 7 of a conveyer, the chains 8 of which are close along the inner side of each wall 4 and each side of the mid-partition 5 and take over sprocket wheels secured on a shaft 10 below the lower end of the chutes 95 and on a shaft 11 below the upper end of the same, the upper shaft being driven by suitable gearing from the engine 12 which drives the rotary wheel 17.

The conveyer chains 8 are protected from 100 the pressure of the snow by angle irons 9 secured to the side walls and mid-partition and projecting over the chains.

The front end of the shaft 13 on which the wheel 17 is secured is supported in a bearing carried on the after end of the mid-partition 5 and passes through a bulk head 18 which extends across the entire width of the flat car between the side walls 4 and separates the plow proper from the space 110 in which is the engine 12 by which the rotary is driven. The wheel is secured on this

shaft 13 close to the bulk head 18 and a downwardly inclined apron 16 receives the snow as delivered from the upper ends of the chutes 6 and delivers it to the wheel 7. This apron is, in the plane of the wheel, curved away from its sweep to each side, as shown in Fig. 3.

The partition 18 follows the circle of the sweep of the wheel and on it is concentrically rotatable a hood 19, embracing approximately half the fan circle, so that it may be turned to leave an opening to either side as desired, through which the snow delivered up the inclined chutes by the conveyors may be thrown clear of the track.

With this plow the smallest depth of snow over the tracks will be lifted by the share 14, conveyed up the chutes 6 and laterally delivered by the apron 16 to the bladed wheel 17, the faces of the blades of which are preferably normal to the plane of rotation, instead of, as is usual, inclined thereto. This enables the snow to be delivered from either side at will by reversing the engine.

Having now particularly described my invention, I hereby declare that what I claim as new and desire to be protected in by Letters Patent, is:

30. 1. A snow plow, comprising the combination with a suitable vehicle, of a bladed wheel rotatably mounted thereon to rotate in a plane normal to the track, an inclined chute leading upward from a share horizontally disposed across the track to a position in front of the bladed wheel and below its axis of rotation, a plow share at the bot-

tom of the shoe, a conveyer moving up the chute, and means for rotating the wheel and operating the conveyer.

2. A snow plow, comprising the combination with a suitable vehicle, of a bladed wheel rotatably mounted thereon to rotate in a plane normal to the track of the vehicle, an inclined chute leading upward from a share horizontally disposed across the track to a position in front of the bladed wheel and below its axis of rotation, said chute having walled sides and divided vertically by a mid-partition, a conveyer movable up each divided half of the chute, the chains of which conveyer are adjacent the side walls and mid-partition, and guards protecting the upper side of the chains.

3. A snow plow, comprising the combination with a suitable vehicle, of a bladed wheel rotatably mounted thereon to rotate in a plane normal to the track, a walled chute leading upward from a share horizontally disposed across the track to a position in front of the bladed wheel and below its axis of rotation, an apron delivering from the upper end of the chute to the underside of the bladed wheel, said apron conforming in the plane of the wheel to the general curvature of its circumference but diverging therefrom toward each side, a hood concentric to the circumference of the wheel and movable concentric therewith that it may be thrown to expose a delivery aperture to either side between its lower edge and the outer edge of the apron.

In testimony whereof I affix my signature.
CHARLES A. SPLAYFORD.
